UNITED STATES PATENT OFFICE.

CHARLES A. SMITH, OF COLUMBUS, OHIO.

CEILING FOR CONCRETE FLOORS.

Application filed May 17, 1922. Serial No. 561,578.

To all whom it may concern:

Be it known that I, CHARLES A. SMITH, a citizen of the United States, residing at Columbus, in the county of Franklin and State of Ohio, have invented a certain new and useful Improvement in Ceilings for Concrete Floors, of which the following is a specification.

The object of this invention generally is to provide an improved ceiling for a concrete floor of the hollow type to which the plaster may be easily applied with the assurance that it will remain in place.

The invention is embodied in the example herein shown and described, the features of novelty being finally claimed.

In the accompanying drawing—

Figure 1 is a vertical sectional view taken transversely of the joists.

Fig. 2 is a sectional view taken at right angles to Fig. 1, as for example upon the line II—II Fig. 1.

Fig. 3 is a detail sectional view of the metallic mold or form with a piece of the metal lath attached thereto.

Fig. 4 is a detail in elevation looking at the right hand side of Fig. 4 and showing how the lath is secured.

Fig. 5 is a section like Fig. 1 showing plaster applied to the lath.

In the views 6 designates a metallic core, mold or dome, the same being of transversely corrugated sheet of inverted trough form and preferably of short lengths suitable for convenient handling. The margins of the sides of these molds are bent to form on the inner side a longitudinal recess V-shaped in cross section and on the outer side a projection or bead. The upper wall 7 of the bead is pierced at regular intervals with a series of slots or holes 8 to receive tongues 9a duly provided on the metal lath 9. The lower flange 10 of the V-shaped portion is somewhat wider than the upper wall 7 and affords a seat for the margin of the lath as best seen in Fig. 3.

To form the floor the molds or domes 6 are set end to end between girders or beams

11 and in parallel rows upon suitable shoring members 12 and 13 as illustrated in Figs. 1 and 2. To strengthen and support the joists to be formed suitable reinforcing rods 14 are placed in the spaces between the molds. Said rods being supported at their ends on the metallic beams. The mixture of concrete is then poured over and between the molds and allowed to harden thereby forming the floor 15 and joists 16.

The holes 8 are made large enough to permit some trickling of soft concrete mixture through them so as to bind the edges of the lath to the mold.

After the shoring is removed a surface excellently adapted to receive the plaster forming the ceiling as illustrated in Fig. 5 is presented.

The forms of the parts can be changed without departing from the gist of the invention as claimed.

What I claim is:

1. A ceiling for a concrete beam floor including, in combination, a sheet metal floor and beam molding core formed with seats at the inner sides of its beam molding margins and a sheet of plaster lath secured between the inner sides of said margins to said seats.

2. A ceiling for a concrete beam floor including, in combination, a sheet metal floor and beam molding core having its margins bent to form longitudinal seats to receive the opposite edges of a sheet of plaster lath, and a sheet of plaster lath secured in said bent margins at the inner sides thereof.

3. A ceiling for a concrete beam floor including, in combination, a sheet metal floor molding core having its side margins bent and perforated to receive tongues of plaster lath, and a sheet of plaster lath having opposite edges provided with tongues and secured between the inner sides of the margins of the core with the tongues extended through said perforations and engaged with said margins.

CHARLES A. SMITH.
